UNITED STATES PATENT OFFICE

116,165

DESIGN FOR AN OVERNIGHT CASE

Harry Kaufmann, West Orange, N. J., assignor to K. Kaufmann & Co. Inc., Newark, N. J., a corporation of New York

Application April 11, 1939, Serial No. 84,198

Term of patent 7 years

To all whom it may concern:

Be it known that I, Harry Kaufmann, a citizen of the United States, residing in West Orange, Essex County, New Jersey, have invented a new,
original, and ornamental Design for an Overnight Case, of which the following is a specification, reference being had to the accompanying drawing, forming a part thereof, in which:

Fig. 1 is a perspective view of an overnight

case showing my new design in closed position;

Fig. 2 is a perspective view thereof with the side compartment in open position.

Fig. 3 is a side elevational view thereof on a slightly smaller scale.

I claim:

The ornamental design for an overnight case,
as shown.

HARRY KAUFMANN.
